UNITED STATES PATENT OFFICE.

CHARLES F. HENDERSON, OF OWOSSO, MICHIGAN, ASSIGNOR TO SAMUEL F. HENDERSON AND DAVID M. ESTEY, BOTH OF SAME PLACE.

PULLEY.

SPECIFICATION forming part of Letters Patent No. 425,322, dated April 8, 1890.

Application filed January 15, 1890. Serial No. 337,011. (No model.)

To all whom it may concern:

Be it known that I, CHARLES F. HENDERSON, a citizen of the United States, and a resident of Owosso, in the county of Shiawassee and State of Michigan, have invented certain new and useful Improvements in Pulleys; and I do hereby declare that the following is a full, clear, and exact description of the invention, which will enable others skilled in the art to which it appertains to make and use the same, reference being had to the accompanying drawings, which form a part of this specification, and in which—

Figure 1 is a longitudinal sectional view through my improved pulley at right angles to and across the axle, and Fig. 2 is a transverse sectional view on the line xx in Fig. 1.

Like letters of reference denote corresponding parts in both the figures.

My invention has relation to pulleys to be used in connection with belting in operating machinery; and it consists in the improvement hereinafter more fully described and claimed, whereby I affix the leather facing of a pulley to the rim of the same in such a manner that it will not become detached, no matter how great a strain the pulley may be subjected to.

Experience has demonstrated that in leather-faced pulleys the leather facing soon becomes loosened from the body of the pulley, owing to the great frictional strain upon the facing, and the object of my invention is to so prepare the rim of the pulley that its leather facing or covering may be affixed to the same in a simple, durable, and lasting manner.

With this object in view the rim of the pulley (shown at A) is first thoroughly cleaned by washing it with good soap or lye or treating it with diluted acid, so that not a particle of grease or oil shall remain. After this has been done and the moisture removed by drying I take a raw onion or piece of garlic, cut it open, and rub it all over the rim of the pulley in such a manner as to provide the same with a thin film or coating of the onion-juice or garlic-juice, and after this film has been absorbed by the pulley-face I take thin split leather of a proper width and cover one side of the leather with a good elastic cement. I prefer

to use for this particular purpose the cement described and claimed by me in another application. After the strip of leather has been thus coated on one side it is wrapped around the pulley tightly, care being taken to exclude all air and avoid the formation of air-bubbles between the leather wrapping and the surface of the pulley. Only a single strip of leather may be used, or several strips may be employed, wound around one another in layers until the requisite thickness has been obtained.

In the accompanying drawings, the letter B designates the inner coating of cement, and C the leather coating or lining in its finished state.

I am well aware that it is not new, broadly, to provide a pulley with one or more strips of leather and paper or other suitable material wound around the pulley in several layers and fastened around by some sort of cement; but, as I have stated at the outset of my specification, practical experience with such pulleys proves that sooner or later the cement loses its grip upon the surface of the pulley, which results in loosening of the leather facing long before the same is worn off. I have found, however, that by treating the pulley with onion-juice or garlic-juice in the manner hereinbefore described the surface upon which the leather facing is to be affixed becomes peculiarly tenacious of the cement spread between it and the leather, thus making the facing lasting, strong, and durable. It is obvious that old pulleys may be treated in this manner as well as new ones, and it will also be found that the treatment may be applied with equal advantage to pulleys made of wood, iron, or other metal.

Having thus described my invention, I claim and desire to secure by Letters Patent of the United States—

1. The hereinbefore-described method of treating pulleys preparatory to providing the same with a facing of leather or similar material, which consists in, first, removing all grease from the surface of the pulley to which the facing is to be affixed, and, secondly, after the pulley has been so treated and dried coating it with a thin film of the juice of onions.

or garlic, substantially as and for the purpose herein shown and set forth.

2. The hereinbefore-described process of affixing a facing or covering of leather or equivalent material to the rim of a pulley, which consists in, first, removing all grease from the face of the rim to which the leather is to be applied; secondly, thoroughly drying the rim to remove all moisture; thirdly, covering the dried rim with a thin film or coating of the expressed juice of onions or garlic, and, fourthly, winding one or more facing-strips of leather or

similar material covered with adhesive cement around the rim of the pulley so treated, substantially as and for the purpose herein shown and set forth.

In testimony that I claim the foregoing as my own I have hereunto affixed my signature in presence of two witnesses.

CHARLES F. HENDERSON.
